UNITED STATES PATENT OFFICE

2,109,545

BREEZE DEFLECTOR

Walter J. McGrane, Chicago, Ill.

Application March 31, 1937, Serial No. 134,079

1 Claim. (Cl. 98—44)

The invention relates to improvements in awnings but more particularly to devices of this character which may be arranged vertically over a window to serve as a breeze deflector, and has for its objects the provision of a device of this character which is simple in structure, easily arranged either in an operative or non-operative position, and highly efficient in use.

Other objects will hereinafter appear.

10 The invention consists in the combinations and arrangements of parts hereinafter described and claimed.

The invention will be best understood by reference to the accompanying drawing in which;

15 Figure 1 is a perspective view of such a device in use embodying the invention;

Figure 2 is a side view of the same;

Figure 3 is an enlarged cross section taken substantially on the line 3—3 of Figure 2;

20 Figure 4 is an enlarged perspective view of the awning hinge shown in Figure 1; and

Figure 5 is a perspective view of a modified form of the invention.

The embodiment of the invention illustrated in the drawing, as best shown in Figs. 1, 2, and 3, comprises a window 10 having a head casing 11 and a sill 12. An awning hinge 13 is mounted on the head casing 11, and a similar hinge 14 is secured to the sill 12 directly beneath the hinge 13. The hinges 13 and 14 are of integral form comprising a flat base 15 having openings 16 facilitating its attachment to a window frame, and outwardly projecting lugs 17 spaced apart and provided with aligned openings 18 adapted to carry suitable hinge pins, and which are arranged substantially at the middle of the window as shown.

Two U-shaped bows 19 and 20 have their upper and lower ends pivoted to the hinges 13 and 14 by suitable pins 21 and 22, respectively, and are arranged to be swung horizontally therefrom independently of each other. Both of the bows 19 and 20 have upper and lower arms 23 extending horizontally and substantially one half the width of the window, and a central vertical portion 24 extending substantially the length of the window, as shown. By this arrangement both of the bows 19 and 20 can be swung to either side of the window.

50 Should it be desired, the use of the hinges 13 and 14 may be avoided, and the arms 23 attached directly to the horizontal surfaces of the head casing 11 and the sill 12 by means of suitable wood screws or the like substituted for the pins 21 and 22, as will be readily understood.

The bows 19 and 20 are provided with independently operable control ropes 25 and 26. The rope 25 is secured to the bow 19 by suitable means leaving both ends free, one free end extending directly to the adjacent side of the window 10, 5 and the other end extending slidably through the ring 27 carried by the bow 20 to the opposite side of the window 10. The free ends are releasably and adjustably secured in the customary manner as and where desired. The rope 26 similarly controls the bow 20 operably through the ring 28 carried by the bow 19, its ends being releasably and adjustably secured to the sides of the window. By this arrangement each of the bows 19 and 20 can be arranged independently of the other 15 and each secured in the various horizontal positions necessary for the operation of the device.

A suitable awning sheet 29, preferably of canvas or like material, is attached at its sides to bows 19 and 20 and at its ends to the pins 21 and 22, 20 as best shown in Figs. 1 and 2. The sheet 29 has parallel sides equipped with tubular pockets 30 and 31 formed by suitable hems held by rows of stitches 32 and 33. The vertical portions 24 of each of the bows 19 and 20 occupy the pockets 30 25 and 31, respectively, as shown, and serve to secure the sides of the awning sheet 29 thereto. It is preferred that the distance between the pockets 30 and 31 be sufficient to allow the bows 19 and 20 to be relatively arranged at an angle of approximately 90 degrees, as shown in Figs. 1, 2, and 3.

The sheet 29 extends at top and bottom, over the arms 23 to the hinges 13 and 14, terminating in upper and lower pointed ends. Adjacent each of these ends a suitable eyelet is provided (not shown), the upper eyelet mounted on the pin 21 of the hinge 13, and the lower eyelet on the pin 22 of hinge 14. By this arrangement the sheet 29 is securely held longitudinally on 40 the bows 19 and 20 and the ends movably attached to the hinges 13 and 14.

A modified form of construction shown in Figure 5 comprises two U-shaped bows 34 and 35 identical with the bows 19 and 20 shown in Figs. 45 1, 2, and 3. The bow 34 is controlled by a rope 36 having one end attached thereto as shown, the free end being used to manipulate and secure the bow 34 in desired position. The rope 36' is secured to the bow 35 by suitable means leaving 50 both ends free, one end extending directly to the adjacent side of the window (not shown) and the other end extending slidably through a ring carried by the bow 34 to the opposite side of the window (not shown). The free ends are releas- 55

ably and adjustably secured in the customary manner as and where desired. By this arrangement the bow 34 may be adjusted in suitable and fixed position, and the adjustment of the bow 35 relative to the bow 34 made by the rope 36, as will be readily understood. An awning sheet 37 is provided having suitable hems 38 and 39 which extend the full length of the top and sides and serve as pockets in which the bows 34 and 10 35 are inserted. Suitable rivets 40 secure the sheet 37 in position on the said bows. It should be noted that the awning sheet extends over the top and down the side terminating at the lower-most corners of the bows 34 and 35 as shown. 15 In use the device is adapted to be arranged at one side of a window to deflect a breeze either into or away from the inside. For this purpose the device is arranged as shown in Figs. 1 and 2. The device may also be used as a screen to obstruct the view as shown in Figure 3, or when it is desired to render the device inoperative it may be collapsed, and held either at or away from the side of the window, as indicated in dotted lines 20 in Figure 3.

While I have illustrated and described a preferred form of construction for carrying the invention into effect, this is capable of variations and modifications without departing from the realm of the invention. I, therefore, do not wish 5 to limit the invention to the precise details set forth, but desire to avail myself of such variations and modifications, as may come within the spirit and scope of the appended claim.

I claim:

A device of the class described comprising a pair of U-shaped bows adapted and arranged to be co-operatively pivoted at their ends; a rope member secured to each of said U-shaped bows; means carried by each of said U-shaped bows to 15 slidably engage the rope member secured to its mate; and a sheet of flexible material adapted to be carried by said U-shaped bow members and adapted to confine their relative movement to approximately 90 degrees. 20

WALTER J. MCGRANE.
